(57) **CLAIM**

The ornamental design for a convertible telephone charger, as shown and described.

DESCRIPTION

FIG. 1 is a front perspective view of the convertible telephone charger of the present invention;

FIG. 2 is a rear perspective view thereof;

FIG. 3 is a rear elevation view thereof;

FIG. 4 is a side elevation view thereof;

FIG. 5 is a top plan view thereof;

FIG. 6 is a front elevation view thereof;

FIG. 7 is an exploded perspective view thereof showing a lighter adapter cover separated from a charger body portion; and,

FIG. 8 is a perspective view thereof showing the lighter adapter cover secured to a pair of AC current prongs of the charger.

The broken lines are for illustrative purposes only and form no part of the claimed design.
